(57) **CLAIM**

The ornamental design for a fuel pump assembly, as shown and described.

DESCRIPTION

This application is related to a commonly-assigned concurrently filed application, "Fuel Pump Assembly" (U.S. patent application Ser. No. 16/123,281, filed on Sep. 6, 2018), the disclosure of which is incorporated herein by reference in its entirety. All of the material from the Fuel Pump application that is essential to the claimed design is included herein. Any material in the Fuel Pump application that is not present herein forms no part of the claimed design.

FIG. 1 is a perspective view of a fuel pump assembly including a sender assembly in a compact position showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate environmental structure and form no part of the claimed design.
